HEINRICH HECHT, OF KIEL, AND WALTER HAHNEMANN AND WILHELM RUDOLPH, OF KITZEBERG, NEAR KIEL, GERMANY, ASSIGNORS TO THE FIRM SIGNAL GESELLSCHAFT M. B. H., OF KIEL, GERMANY.

SUBMARINE SOUND TRANSMITTER.

Application filed February 4, 1921. Serial No. 442,576.

(GRANTED UNDER THE PROVISIONS OF THE ACT OF MARCH 3, 1921, 41 STAT. L. 1313.)

To all whom it may concern:

Be it known that we, HEINRICH HECHT, WALTER HAHNEMANN, and WILHELM RUDOLPH, citizens of the German Republic, 5 and residing at Kiel and at Kitzeberg, near Kiel, county of Schleswig-Holstein, State of Prussia, have invented certain new and useful Improvements in Submarine Sound Transmitters, for which we have filed applications for patent in Germany, on May 10 3, 1918; Denmark, on May 2, 1919; Sweden, on May 14, 1919; Norway, on May 15, 1919; Holland, on June 16, 1919, and June 23, 1920; Spain, on July 7, 1920; Belgium, 15 on July 8, 1920; France, on July 8, 1920; Italy, on July 9, 1920; England, on July 10, 1920, and of which the following is a specification.

This invention relates to sound producers 20 in liquids, particularly for submarine sound signalling, in which the exciting force acts on the member radiating the sound waves by means of a lever.

Devices are known particularly in connection with producers of sound in air, in 25 which a lever is used in order to transfer the exciting force on to a diaphragm, both for increasing and diminishing the motion amplitudes at the radiator. So far as they 30 cause an increase in the motion amplitudes at the radiator they are satisfactory in the case of air; so far as they diminish the same they operate for air sound in an entirely unfavourable sense, because with highly compressible media (gases) it is above all of importance to produce large motion amplitudes.

Furthermore, all pure lever systems which 40 are known use a bearing for the lever which is not very favorable for any acoustic purposes, inasmuch as the lever is usually pivoted in trunnions or between points. While such pivotal lever arrangement might be permissible in air and might give results, although of low efficiency, such an arrangement is absolutely unpermissible in submarine sound receivers or transmitters for the following reasons: In acoustic transmitters used in air very large motion amplitudes are being dealt with, so that a slight play in the pivotal joints would not affect the apparatus to the extent of rendering it useless. In submarine sound transmitters

the customary amplitudes are approximately one-hundredth of that in air and amount to 55 only small fractions of a millimeter. Therefore, pivotal joints which are journaled with such exactness that they do not neutralize by their lost motion, the amplitude of the acoustic structure, can be manufactured 60 only with the utmost difficulty and would therefore be useless for practical purposes.

For this reason in accordance with the present invention the elements *c*, *c'* are attached to the lever and the diaphragm, respectively to the masses *m* or *g* in the several modifications, by rigid means, such as soldering or welding, so that a "jointless" connection is thereby established. Element *c* attaches lever *a* to mass *g* or *m* yieldingly in 70 the direction of vibration but rigidly at right angles thereto, whereas element *c'* attaches lever *a* to the diaphragm rigidly in the direction of vibration but yieldingly at right angles thereto. We are not aware that 75 the prior art discloses connections of this character and for this purpose in order to increase the efficiency of submarine sound producers.

It has further been proposed with diaphragm transmitters for submarine sound signals to interpose between the points of engagement of the exciting force and the diaphragm an acoustic oscillatory structure 80 tuned to the frequency of the exciting force, 85 the diaphragm being connected to the oscillatory structure at such points which execute small amplitudes while the exciting force engages the oscillatory structure at points of large amplitudes. Such devices operate 90 correctly from an acoustic point of view and with good efficiency, but since the diaphragm equally constitutes an acoustic oscillatory structure by itself they are thus two-wave devices, i. e. systems having two 95 frequencies, while for signal transmission only one definite wave frequency is used.

Finally, in none of the known devices has it been recognized that the lever must be so dimensioned that it acts itself as a rigid 100 whole in respect to the frequency of sound used.

Compared with the above the invention consists, above all, in connecting the lever which transmits the exciting force to the 105 radiating member between the point of en-

gagement of the exciting force and the radiating member so that the former engages on the long lever arm and the latter on the short lever arm, the lever having bending portions instead of pivots, but being advantageously constructed otherwise as a rigid whole in respect to the sound frequencies used.

By the term "rigid" in the connection as used, we mean that the lever should constitute a rigid, non-flexible element at the rate of vibrations employed, it being quite thinkable that a lever which is "rigid" in the above sense within a given range of frequencies will not be so at another frequency or range of frequencies.

As regards the form which the lever itself should assume, much latitude is left to the designer. The requirement of rigidity would lead, with massive construction of the lever, in particular with high sound frequencies to structures of rather considerable mass. It is therefore advantageous to make the structure used as a lever stout in the direction of movement but as narrow as possible in the direction at right angles to the same. For stiffening in the lateral direction its cross-section should advantageously have the form of a single or double T-beam, or other suitable shape.

Furthermore, the lever for distributing the engaging forces according to the invention tapers from the point of engagement of the large forces acting with small amplitudes towards the points of engagement of the small forces acting with large amplitudes. In this way a further very considerable saving in weight is produced.

As a fixed abutment for the lever the casing of the transmitting apparatus itself or any other sufficiently heavy or rigid body located in the vicinity can be used.

If the lever is connected with an elastic oscillatory diaphragm acting as a radiator whose natural frequency agrees with the signal frequency, taking into consideration the co-oscillating lever and water masses, the advantage is obtained that the transmitter develops a maximum strength of sound in a single frequency, therefore it works with the best possible efficiency. With continual excitation of the transmitter, the exciter frequency in this case must coincide with the natural frequency of the radiator as the single oscillatory structure present.

It is possible, however, by using levers constructed according to the invention, to produce also transmitters which can be excited with good efficiency with any suitable frequency whatever, that is, which permit any desired change of wave. For this it is necessary that the natural frequency of the radiator structure lies far below or far above those ranges of pitch within which a change

of wave is to take place. The former is in general to be preferred. The radiator is then advantageously constructed over a definite range as a piston-like rigid plate and provided with a flexible rim portion.

In the drawings, constructional examples of the invention are represented diagrammatically. In these drawings:

Fig. 1 is a transmitting arrangement in which the lever is fastened at one side to the transmitter casing.

Fig. 1^a is a detail of Fig. 1.

Fig. 2 is a transmitting arrangement in which the lever at its free end terminates in a large mass.

Fig. 3 is a similar arrangement in which the lever co-operates with a piston-like diaphragm.

In Fig. 1 *a* represents the lever, *b* a sound radiator or diaphragm on which the lever *a* acts. The lever *a* is connected at one of its ends with the transmitter casing *g*, at a further place preferably near the previously mentioned end with the sound diaphragm. The connections are effected through strips of metal *c* and *c'* shaped similar to fish-plates, and which are so disposed that strip *c* yields in the direction of vibrations but forms a rigid connection at right angles thereto, and strip *c'* forms a rigid connection in the direction of vibrations and yields to bending forces at right angles thereto. At the second end of the lever, at the point of engagement of the exciting force in the examples shown in the drawing, the armature *d* of an electro-magnet is mounted which co-operates with the field magnet *e*. The latter is excited by a source *w* of alternating current.

Fig. 1^a shows a transverse section through the lever along the line *n*—*n* Fig. 1.

In Fig. 2 the casing *g*, serving in Fig. 1 as a fixed abutment for the lever, is replaced by a heavy mass *m*, which remains stationary in space on movement of the lever on account of its great inertia which prevents it from following the oscillations. The constructional forms of Figs. 1 and 2 are particularly suitable for transmitting a particular sound frequency, which is determined by the natural frequency of the sound diaphragm.

In the constructional example of Fig. 3, which serves for transmitting any desired frequencies, in place of a sound plate of a frequency suitable for the sound pitch, a rigid plate *p* with a pliable edge portion is used which is moved parallel to itself outwards and inwards by the movement of the lever. In order to avoid detrimental evasive movements of the sound transmitting liquid, i. e. movements of the water from one part of the diaphragm surface to another, the flexible marginal portion of the diaphragm is advantageously stiffened by ribs *i*,

i which permit of flexures or bending only at the inner and outer edges *r* of this marginal portion, or in other words cause the edges *r* to act as pivots.

5 The excitation of a transmitter according to the invention can of course also take place in another way, for example, by hydraulic or other mechanical impulse in a periodic or continuous form, particularly 10 also by striking; also there is no restriction to the form of lever shown, since any lever of uniform shape may be used.

We claim:

1. A submarine sound producer comprising 15 a sound radiating member, a lever rigid in the direction and within the range of the exciting vibrations and a jointless connection between said lever and the sound radiating member, said connection being rigid in the 20 direction of the vibrations but yielding at right angles thereto, and an exciting device adapted to vibrate the lever; the point of the lever acted upon by the exciting device and the junction point with the sound radiating 25 member being disposed at portions of the lever to cause the first mentioned point to execute larger motions than the junction point with the sound radiating member.

2. A submarine sound producer comprising 30 a sound radiating member, a lever rigid in the direction and within the range of the exciting vibrations and a connection between said lever and the sound radiating member, said connection being rigid in the direction 35 of the vibrations but yielding at right angles thereto, a large idle mass yieldingly but jointlessly connected to the lever, and an exciting device adapted to vibrate the lever, both of said yielding connections being 40 disposed at suitable portions of the lever to cause the point of the lever acted upon by the exciting device to execute larger motions than the point of the lever connected to the radiating member.

45 3. A submarine sound producer comprising a sound radiating member, a lever rigid in the direction and within the range of the exciting vibrations and a connection between 50 said lever and the sound radiating member, said connection being rigid in the direction of the vibrations but yielding at right angles thereto, a large idle mass yieldingly but jointlessly connected to the lever, and an exciting device adapted to vibrate the lever, 55 both of said yielding connections being dis-

posed at suitable portions of the lever to cause the point of the lever acted upon by the exciting device to execute larger motions than the point of the lever connected to the radiating member, said large idle mass being embodied in the producer frame surrounding the radiating diaphragm. 60

4. A submarine sound producer comprising 65 a sound radiating member, a lever in the form of a T shaped element, having its up-standing flange extending in the direction of the sound vibrations so as to make it rigid at the rate of vibration of the sound employed, a jointless connection between said lever and the sound radiating member, said connection 70 being rigid in the direction of vibration but yielding at right angles thereto, and an exciting device adapted to vibrate the lever; the point of the lever acted upon by the exciting device and the junction point with the 75 sound radiating member being disposed at suitable portions of the lever to cause the first mentioned point to execute larger motions than the junction point with the sound radiating member. 80

5. A submarine sound producer comprising 85 a sound radiating member, a lever in the form of a T shaped element, having its up-standing flange extending in the direction of the sound vibrations so as to make it rigid 90 at the rate of vibration of the sound employed, a jointless connection between said lever and the sound radiating member, said connection being rigid in the direction of vibrations but yielding at right angles thereto, and an exciting device adapted to vibrate 95 the lever, the point of the lever acted upon by the exciting device and the junction point with the sound radiating member being disposed at suitable portions of the lever to cause the first mentioned point to execute larger motions than the junction point with the sound radiating member, said lever being tapered from said junction point towards the end adjacent to said exciting device. 100
